UNITED STATES PATENT OFFICE.

HENRY S. HUNT, OF CATO, NEW YORK.

DESIGN FOR AN AERATOR FOR CREAM-SEPARATORS.

SPECIFICATION forming part of Design No. 30,014, dated January 17, 1899.

Application filed December 21, 1898. Serial No. 699,964. Term of patent 14 years.

To all whom it may concern:

Be it known that I, HENRY S. HUNT, a citizen of the United States, residing at Cato, in the county of Cayuga, in the State of New York, have invented and produced a new and original Design for Aerators for Cream-Separators, of which the following is a specification, reference being had to the accompanying drawings, forming part thereof, in which—

Figure 1 shows a side view thereof. Fig. 2 shows a vertical section thereof.

As shown in the accompanying drawings, the leading or material feature of my design consists of a cylindrical body *a*, having a cylindrical cap *b*, mounted in one end thereof,

said cap terminating in a convexed mantel *c*. The periphery of the cap *b*, adjacent the point where it receives the mantel, is provided with openings or perforations *d*.

Having described my invention, what I claim, and desire to secure by Letters Patent, is—

The design for an aerator for cream-separators, as herein described and shown. 25

In witness whereof I have hereunto set my hand this 19th day of December, 1898.

HENRY S. HUNT.

Witnesses:

M. A. FRANKLIN,
HOWARD P. DENISON.
